No. 832,701.

PATENTED OCT. 9, 1906.

W. S. SANBORN.
SASH WEIGHT.
APPLICATION FILED MAR. 22, 1906.

UNITED STATES PATENT OFFICE.

WILLIAM S. SANBORN, OF BELMONT, MASSACHUSETTS.

SASH-WEIGHT.

No. 832,701.

Specification of Letters Patent.

Patented Oct. 9, 1906.

Application filed March 22, 1906. Serial No. 307,513.

To all whom it may concern:

Be it known that I, WILLIAM S. SANBORN, a citizen of the United States, and a resident of Belmont, in the county of Middlesex and

5 State of Massachusetts, have invented an Improvement in Sectional Sash-Weights, of which the following description, in connection with the accompanying drawings, is a specification, like numerals on the drawings 10 representing like parts.

This invention has for its object the production of a novel and efficient sectional sash-weight combining a maximum weight for volume in each member or unit, an absolutely safe and reliable interlock or coupling 15 between adjacent units, and cheapness and simplicity of manufacture.

Certain practical conditions govern the production of a commercially-successful sectional sash-weight, one of the most important of which is the manufacture thereof at practically a nominal cost, for if this condition is not fulfilled the weight cannot be successfully marketed. Given a satisfactory 20 cost of production, it is necessary that the construction of the members, units, or sections be such that they can be easily and quickly connected, and when connected they must be so locked together as to admit of 25 perfect safety in handling, and they must be usable without the intervention of a master or head piece to connect them with the sash chain or cord.

As will appear hereinafter, the sectional 30 sash-weight embodying my invention fulfills in a most satisfactory and efficient manner all of the conditions hereinbefore set forth.

The various novel features of my invention will be fully described in the subjoined specification and particularly pointed out in the 40 following claims.

Figure 1 is a side elevation of one form of sash-weight embodying my invention, two members or units being coupled together. 45 Fig. 2 is a front elevation thereof. Figs. 3 and 4 are upper and lower end views, respectively, of one of the units or members. Fig. 5 is a perspective view of one of the members. Fig. 6 shows two members locked together, 50 but at right angles to each other, the head end of the horizontal member being broken out and in sections. Fig. 7 is a similar view, but showing the two members at a greater angle. Fig. 8 is a longitudinal section on the 55 line 8, Fig. 9, of a modification to be re-

ferred to. Fig. 9 is a front elevation thereof, and Fig. 10 is a partial section and side elevation of yet another modification to be referred to.

In the present embodiment of my invention the sash-weight member or unit is made as a casting comprising an elongated body 1, rectangular in cross-section and having at its lower end a central projecting and flat-sided hook 2, having a circular opening 3 and a front entrance 4, the upper and lower faces 5 and 6 of the entrances being parallel and at right angles to the length of the body, as clearly shown in Fig. 1. The lower front corner of the hook is rounded at 7 for a purpose to be described. At its upper end the member is provided with a slot or recess 8, extending through the body from front to back and of a depth very slightly greater than the length of the hook and slightly wider than the thickness of the hook. A cross-bar 9 spans the recess from side to side, with a clearance above and below it, the front and back faces 10 11 of said bar being flat and parallel to each other and at right angles to the faces 5 6 of the hook-entrance, while the top and bottom edges 12 of the cross-bar are convexed, preferably on substantially the curvature of the hook-opening 3. The thickness of the cross-bar is slightly less than the height of the hook-entrance 4, and its height is such that it will pass into and turn within the hook-opening 3 of the next unit or member when coupled thereto. The upper front corners of each member are rounded off, as at 13, oppositely to but with a curvature similar to that of the part 7 of the hook.

In order to connect two members, they are brought into position at right angles to each other, with the hook of the upright member 95 inserted in the recess of the horizontal member, the cross-bar 9 of the latter then lying opposite the hook-entrance. Now while maintaining such right-angled position the members are given a relative movement to 100 pass the cross-bar through the hook-entrance and into the opening 3 of the hook, as shown in Fig. 6. Now if the members are straightened out by a swinging movement (see Fig. 7) to the position shown in Figs. 1 and 2 the 105 cross-bar of the lower member will turn in the hook-opening and the members are in operative position interlocked or coupled together. The broad part of the cross-bar is now opposite or in front of the hook-entrance, 110

and manifestly the members cannot become uncoupled.

Supposing the coupled members to be turned into the position shown in Fig. 6, they 5 cannot then be unlocked or disconnected unless there be a relative separating movement of the upright member to the left or the horizontal member to the right to cause the cross-bar of the latter to pass through and 10 out of the hook-entrance of the upright member. This is a very important feature of my invention, for it is practically impossible to unlock when two members are at right angles unless the hands of the workman impart 15 the additional movement referred to. Thus with two or more units coupled together and ready to be drawn up into the weight-box from a horizontal position on the window-sill where the units were assembled the lifting 20 movement brings the first unit upright and at right angles to the next before the latter begins to lift. Unless at this instant a positive backward movement is given to the upright unit the two coupled units cannot possibly 25 become uncoupled, and the back of the weight-box acts to prevent any such backward movement of the upright member. I thus obviate any possibility of disconnected members falling into the street while the 30 weights are being installed, the modern high buildings making such accidental falls extremely dangerous.

As every unit is made like all of its fellows, except as to actual weight, and the latter is 35 determined by the length of the unit, any one will interlock with any other one and will stay locked until positively and purposely unlocked by the intervention of human agency, as described.

40 The coupling of the units is a momentary matter, requiring no fitting or adjusting, and as the sash chain or cord is connected with the topmost unit by its cross-bar no master or head-piece or special connection is required.

45 The units are made in standard weights, so that knowing the approximate weight of the sash to be hung the requisite counterbalance is made by merely picking out the particular units necessary and coupling them together.

50 So simple is the interlocking and so obvious is the procedure that no directions are required, while it is secure and strong and cannot become unlocked accidentally.

By an inspection of the drawings it will be seen that the loss of weight due to the form of the coupling is reduced to a minimum, for, viewing Figs. 1 and 2, the hook of one unit 55 practically fills the recess of the adjacent unit, the only losses of material being opposite the rounded corners 13 and 7. This is necessary in order to permit the angular movement of the coupled units into coupling 60 position; but it will be seen that the mass of

metal in two or more coupled members is almost the same as if said members were made in one solid casting.

Sash-weights are made from the cheapest and poorest class of scrap-iron, ranging from 70 old tin cans to stove-plate scrap, and as sectional sash-weights must compete in price with a solid weight the sectional weight must be ready for use practically as it comes from the mold. The form of the unit, therefore, 75 must be such as can be cheaply molded and cast, and this requirement is met herein, as will be manifest, and no grinding, fitting, chipping, or filing is necessary when the unit is taken from the mold, thus reducing the labor cost to its lowest terms. As a matter of fact nothing is required other than a slight tumbling to remove the sand adhering to the casting.

It frequently happens that in a sectional 80 sash-weight the combination of iron and lead units would be of very great value—that is, a weight composed of one or more units of cast-iron and coupled thereto one or more units of lead—or at times the entire 85 weight might with great advantage be composed of lead units. The lead is soft, however, liable to bend, and possessing relatively slight tensile strength, so that cast-lead units cannot in practice be interlocked with each 90 other or with cast-iron units unless some provision is made for strengthening the lead. 95 In my present invention I have provided means for so strengthening or reinforcing the lead that it can be cast in the same form 100 as the cast-iron unit and used successfully. To this end I reinforce the weak points of the lead units and will refer to Figs. 8 to 10 of the drawings.

Referring to Figs. 8 and 9, the body portion 20, having the recess 21 at the upper end and the projecting hook 22 at the lower end, and the front entrance 23 for the hook are all as hereinbefore described, but are cast of lead; but the cross-bar 24 is cast-iron, and the 105 hook-opening is reinforced by a hook-like lining 25 of cast-iron. The cross-bar 24 and reinforce 25 are connected by an integral shank 26, bent or offset at its upper end at 27 to connect with one end of the cross-bar, as 110 clearly shown in Fig. 9. The shank, cross-bar, and reinforce for the hook will be cast in one piece of iron and then laid in the mold for the lead body as a species of core, the molten lead being poured around it, embedding 115 the iron in the mass of lead composing the main portion of the unit. The offset 27 serves to clear one side of the recess 21 in the body of the unit, while the connection between the cross-bar and the reinforce 25 for 120 the hook transmits the tensile strain directly from one to the other, taking the strain from the lead forming the hook of the unit.

In Fig. 10 I have shown the lead hook 28 reinforced by a section of iron pipe 29, the 125

lead being cast about the same, and the cross-bar is made by inserting a flattened piece of piping 30, and the lead when poured fills the same. The piping would be extended far enough each side to be firmly embedded in the lead during the casting operation. The arrangement provides a reinforce and a hard wearing-surface for the parts affected and prevents bending of the hook or of the cross-bar.

By combining the lead and iron to make a lead unit feasible a very material saving in cost is effected, for the total weight of the counter-balance could be made up of one-third to one-half lead units, and the balance cast-iron, where otherwise a non-sectional weight entirely of lead would have to be used. As the cost of iron is only about one-quarter the cost of lead per pound, the saving will be manifest.

Having now fully described my invention, what I claim as new, and desire to secure by Letters Patent, is—

1. A sectional sash-weight member having at one end a flat-sided, central, projecting hook provided with a front entrance, and at its other end provided with a recess open front and back to receive the hook of a contiguous member, and a cross-bar in the recess having parallel front and back faces at right angles to the faces of the hook-entrance and a less distance apart than the faces of the hook-entrance, whereby two members can be coupled or uncoupled only when turned at right angles to each other and given a relative movement in such position, the depth of the cross-bar being greater than the height of the hook-entrance.

2. A sectional sash-weight member rectangular in cross-section and having at one end a flat-sided projecting hook having a circular opening and a front entrance, and at its other end correspondingly recessed from front to back, and a cross-bar in the recess having convex upper and lower edges and upright, parallel front and back faces at right angles to the faces of the hook-entrance and adapted to pass through the entrance of the hook of the next member when two members are turned at right angles and moved relatively while in such position, the curvature

of the upper and lower edges of the cross-bar corresponding to the curvature of a hook-opening.

3. A sectional sash-weight member rectangular in cross-section and having at one end a flat-sided projecting hook having a circular opening and a front entrance, and at its other end correspondingly recessed from front to back, the front upper corners of the member being rounded and the end of the hook being similarly but oppositely rounded, and a cross-bar in the recess of greater depth than the hook-opening and having upright front and back faces parallel to each other and at right angles to the opposed faces of the hook-opening, the height of the latter being greater than the thickness of the cross-bar, to permit passage of the cross-bar of one member into and out of the hook of another member when said members are turned at right angles and given relative movement in such position.

4. A sectional sash-weight member having a projecting hook at one end provided with a front entrance, and at its other end having a recess, and a cross-bar spanning the recess, whereby the hook of one member can enter the recess in the adjacent end of the next member and interlock with its cross-bar, means to permit coupling and uncoupling of two members when at right angles to each other and moved relatively while so positioned, and a reinforce for the hook and cross-bar, to increase the resistance thereof to tensile strain.

5. A cast-lead sectional sash-weight member having at one end a central projecting hook with a front entrance and at its other end provided with a recess open front and back, a cross-bar in the recess, and a hard-metal reinforce for the cross-bar and hook, embedded in the lead and increasing the resistance of the hook and cross-bar to tensile strain.

In testimony whereof I have signed my name to this specification in the presence of two subscribing witnesses.
